CLAIM

The ornamental design for a tray for filling of vials syringes and cartridges for fill and finish machines as shown and described.

DESCRIPTION

FIG. 1 is a bottom perspective view of a tray for filling of vials syringes and cartridges for fill and finish machines showing our new design;

FIG. 2 is a bottom view thereof;

FIG. 3 is an enlarged view of area 3 in FIG. 2;

FIG. 4 is a top view thereof;

FIG. 5 is a front view thereof;

FIG. 6 is a back view thereof;

FIG. 7 is a right side view thereof; and,

FIG. 8 is a left side view thereof.

The dashed lines and the half-tone shaded area within the dashed lines depict portions of the tray for filling of vials syringes and cartridges for fill and finish machines that form no part of the claimed design. The dot-dash lines in the drawings depict boundaries of the enlarged views that form no part of the claimed design.
